UNITED STATES PATENT OFFICE.

THADDEUS F. BAILY, OF ALLIANCE, OHIO.

ELECTRIC FURNACE.

Application filed August 28, 1923. Serial No. 659,738.

To all whom it may concern:

Be it known that I, THADDEUS F. BAILY, a citizen of the United States, residing at Alliance, in the county of Stark and State 5 of Ohio, have invented certain new and useful Improvements in Electric Furnaces, of which the following is a specification.

This invention relates to improvements in electric furnaces of the type in which a current of electricity is passed through resistance material to produce the necessary heat, and more particularly to a resistance trough located above and surrounding the hearth up which the material to be heated is placed.

15 It is customary to support this trough upon radial supporting walls which interfere with free access to all parts of the hearth, limiting the working surface of the hearth considerably and causing hot spots 20 around the under side of the trough.

The objects of the present invention are to provide in a furnace of this type, a trough containing the resistance material which is supported entirely from the side 25 walls of the heating chamber, thus leaving the entire hearth unobstructed and easily accessible.

Another object of the improvement is to provide a resistance trough of this character 30 which is mounted in a removable section of the furnace and which comprises a removable and replaceable unit, which may be easily removed from the furnace and replaced when the trough is burnt out.

35 The above and other objects may be attained by providing a pair of spaced, concentric, annular walls of refractory material, the outer wall being connected directly to the walls of the heating chamber 40 and the inner wall being supported upon an arched, annular bottom member mounted upon the annular outer wall, a suitable granular carbonaceous material being located in the trough, electrodes extending into 45 the same, and an insulated section of fire brick wall surrounding the trough and with a section of metal shell upon which the electrode terminals are supported.

An embodiment of the invention thus set 50 forth in general terms is illustrated in the accompanying drawings, in which—

Figure 1 is a vertical, sectional view on the line 1—1, Fig. 2; and

55 Fig. 2, a horizontal section on the line 2—2, Fig. 1.

Similar numerals refer to similar parts throughout the drawing.

The brick work 1 of the furnace may be supported upon a metal plate 2, and is preferably formed of fire brick having the 60 lining 3 of suitable heat resisting material forming the hearth 4, which may be concaved as shown in Fig. 1.

A door opening 5 is provided in one side of the furnace above the hearth, and a pouring spout 6 communicating therewith, the door opening being normally closed by the door 7.

The brickwork is surrounded by a metal shell 8, preferably spaced therefrom, and 70 provided at its upper edge with a sand trough 9.

A removable circular section is supported upon the structure above described, and carries the heating element. This section 75 comprises the circular brick wall 10, surrounded by the insulating material 11, such as kieselguhr or the like, a circular steel shell 12 covering the outside of the section, and provided with the depending angular 80 flange 13 arranged to be seated in the sand trough 9, forming a sand seal between the sections of the furnace.

An annular rib 14, of carborundum or similar refractory material is built in the 85 wall 10 and provided with the beveled edge 15. The annular outer wall 16, of the trough is formed of carborundum or the like and rests upon the rib 14, preferably engaging the inner face of the wall 10. 90

The annular bottom wall 17 of the trough is also formed of carborundum or similar refractory material, and is arched as shown in Fig. 1, the outer beveled edge 18 thereof resting upon the beveled edge 15 of the rib, 95 the inner edge being beveled as at 19 to receive the beveled lower edge 20 of the annular inner wall 21 of the trough, which is also formed of carborundum or the like. The trough is thus supported entirely upon 100 the wall 10 which forms a part of the heating chamber of the furnace.

This annular trough is filled with a resistance body, consisting of a carbonaceous material in granular form, such as crushed 105 coke, graphite, carbon or the like, said resistance body being designated by the numeral 22.

Embedded in the resistance material, preferably at diametrically opposite sides of the 110

trough, are the electrodes 23, said electrodes extending through the wall of the removable section of the furnace, as shown in the drawing. It will be understood that these 5 electrodes are located in an electric circuit, said construction being well known in this art, electric conductors 24 being connected to the terminals of the electrodes and leading to a suitable source of electricity. When 10 the current is supplied to the electrodes, it will be connected from one electrode to the other through the resistance material, thus raising the resistance material to an intense heat.

15 The terminal of each electrode is supported upon a bracket 25 connected to the shell of the removable section of the furnace, thus permitting this section to be removed as a unit, after the electric conductors have 20 been disconnected from the electrodes, the entire resistance element being thus contained in the removable section.

A metallic sand trough 26 is provided at the upper edge of the shell of the removable 25 section and the roof, comprising the brick-work 27 is covered with a metal shell 28 having the depending flange 29 which enters the sand trough 26, forming a sand seal between the removable section and the roof. 30 Thus, when the resistance trough is burned out, the roof section may be removed and the removable section, carrying the resistance element, may be lifted from the hearth section and replaced by a new resistance section, the roof section being returned to its place, and the furnace is ready for operation.

It will thus be seen that the annular trough containing the resistance material is 40 located above the hearth and surrounds the same, and is supported entirely upon the side wall of the heating chamber, thus leaving the entire hearth unobstructed, providing a larger working surface upon the 45 hearth, and leaving all parts of the same easily accessible, and eliminating the hot spots around the trough caused by the usual supporting piers.

I claim:

50 1. In an electric furnace having a heating chamber and a hearth therein, an arched re-

sistance trough located above the hearth and supported entirely upon the side walls of the heating chamber and in juxtaposition thereto.

2. In an electric furnace having a heating chamber and a hearth therein, a rib upon the walls of the heating chamber, above the hearth, and an arched resistance trough supported upon said rib and in 60 juxtaposition to the walls of the heating chamber.

3. In an electric furnace having a heating chamber and a hearth therein, an annular rib upon the walls of the heating chamber, 65 above the hearth, said rib having a beveled inner edge, and a resistance trough comprising an annular outer wall supported upon the top of said rib, an arched annular bottom wall supported upon the beveled edge 70 of the rib and an annular inner wall supported upon the bottom wall.

4. In an electric furnace having a heating chamber and a hearth therein, an annular rib upon the walls of the heating chamber, 75 above the hearth, said rib having a beveled inner edge, and a resistance trough comprising an annular outer wall supported upon the top of the rib, an arched bottom wall supported upon the beveled edge of 80 the rib and provided with a beveled inner edge and an annular inner wall supported upon the bottom wall and provided with a beveled lower edge mounted upon the beveled inner edge of the bottom wall. 85

5. In an electric furnace, a hearth section, a removable section mounted thereon, a resistance element in the removable section and a removable roof mounted upon the removable section.

6. In an electric furnace including a hearth and a roof, a removable section between the hearth and roof, a resistance trough mounted in the removable section, electrodes in said trough extending through 95 the wall of the removable section and means mounted upon said removable section for supporting the terminals of the electrodes.

In testimony that I claim the above, I have hereunto subscribed my name.

THADDEUS F. BAILY.
